UNITED STATES PATENT OFFICE.

FRANK S. BUCK, OF SPRINGFIELD, VERMONT, ASSIGNOR, BY MESNE ASSIGNMENTS, TO FITZ-EMPIRE DOUBLE PIVOT LAST CO., OF ROCHESTER, NEW YORK, A CORPORATION OF MAINE.

MACHINE FOR TURNING IRREGULAR FORMS.

1,330,841.

Specification of Letters Patent.

Patented Feb. 17, 1920.

Application filed April 10, 1915, Serial No. 20,432. Renewed October 25, 1918. Serial No. 259,716.

To all whom it may concern:

Be it known that I, FRANK S. BUCK, a citizen of the United States, and resident of Springfield, in the county of Windsor and 5 State of Vermont, have invented certain new and useful Improvements in Machines for Turning Irregular Forms, of which the following is a specification.

The present invention relates to machines 10 for turning irregular forms and particularly to machines for cutting lasts. It is peculiarly adapted for successful operation according to the principles disclosed in Patent No. 1,137,117, granted April 27, 1915.

15 Prior to my invention set forth in the said patent, one great difficulty experienced in cutting lasts was the absolute failure of the machine to reproduce the more sharply concaved portions of lasts of many styles, due to 20 the comparative flatness of the large model wheel which had to be used on these machines. This necessitated digging out these concavities in a further expensive and inaccurate operation.

25 My invention disclosed in said Patent No. 1,137,117 placed the cutter axis at an acute angle with the work axis in the direction of feed of the cutter and thereby secured the advantages of a small model wheel

30 and cutter head with consequent accuracy in reproduction which had been unattainable with parallel work and cutter axes; an arrangement of the roughing and finishing cutters along and close to the angled axis

35 which brought the cutting edges into more efficient working relation with the block than had been possible with prior types and, at the same time, secured compactness which had been, until then, unattained in a practical

40 last lathe cutter head; and avoided, among others, difficulties incident to compressive and bending stresses in the cutter shaft, to the catching or "hogging" of the cutter into the work, and to the boring (as

45 distinct from shaving) action of the cutter head which had arisen in connection with attempts to incline the axis in the wrong direction.

The angle between the cutter axis and the 50 work axis in the machine shown in the patent referred to was about eighty degrees. I have found by subsequent experimentation that the advantages of my prior invention are secured to a much greater extent by an

angle of less than forty-five degrees, and 55 that other advantages of great importance result from such a sharply acute angle.

The more acute angle has increased the advantages secured by my former invention of drawing the cutter head over the 60 work instead of pushing it over or into the work, and secured even greater freedom from vibration in the cutter spindle, and absence of the gouging or "hogging" effect 65 met with where a cutting tool is pointed into the work, and is still ample to secure clearance between the work and the cutter arbor and its supporting mechanism, while permitting the use of a model wheel and cutter as small as three inches in diameter. 70 Secondly, such a sharply acute angle also permits a radial reorganization of the type of cutter head used. A finishing cutter head on a shaft far from parallelism with the axis of the work must necessarily be 75 substantially spherical, if it is to reproduce the concavities of the model properly. Cutter heads of the spheroidal type are expensive, difficult to grind, repair and adjust, and are not as clean cutting as the type 80 about to be mentioned.

An axis at a considerable distance from the perpendicular to the work axis permits the use of a flat disk-shaped finishing cutter head of convenient size for economic construction and operation, and of proper effective contour for accurate reproduction of the model. This type of cutter head had never before been incorporated in a practical small cutter head machine. Such a 85 cutter head on an inclined axis has been suggested before, but the axis was inclined in the wrong direction, and consequently the machines in question were subject to various serious disadvantages such as digging into 90 the work, an expensive and cumbersome plural shaft construction, etc., in the effort to avoid which the cutter axis was swung toward the perpendicular by other experimenters, who thereupon sacrificed the advantage of the disk form of cutter head. The invention of said Patent No. 1,137,117 95 swung the axis beyond the perpendicular, but the additional sharpening of the angle secured by the present invention permits 100 the use of a finishing cutter head of the flat-disk type, with all its practical advantages, while retaining and increasing the advan-

ages of the invention of the previous patent.

Another distinct advantage resulting from the more acute angle of the present invention arises in connection with the turning of modern "high coned" lasts. These lasts rise sharply and for a considerable distance from the flat top of the cone to the top of the instep, thus forming a last with a long extended instep, or so-called "high cone." It is impossible to cut a sharp lateral projection on a last with a cutter head of the disk type on an axis near the perpendicular to that of the work. I have found that the sharply acute angle of my present invention permits the production of high coned lasts of the most extreme styles desired.

Accordingly I regard a cutter shaft inclined toward the direction of feed at an angle of less than 45° with the axis of the work as an important feature of my invention.

Another important advantage of the invention proceeds from the shape of the cutter head itself. The cutter head of the present invention is conical or pear-shaped with the large end toward the axis of the work. This construction has several advantages. It stiffens and supports the necessarily projecting end of the cutter arbor, distributes the cutting action along it and enables the removal of the wood in thinner chips with less vibration and bending moment in the arbor. With the axis inclined as described, the finishing blades are at the large end of the cutter head and are therefore given a rapid velocity, as is necessary for smooth work, while the roughing blades, which have the heaviest work to do, but which are not required to do it smoothly nor to move at high speed, are close to the axis and therefore supported firmly and simply. This construction, moreover, has an important bearing on the matter of cutting high coned lasts, already mentioned. The conical or pear-shaped cutter head situated as described permits a more acute angle of the axis than would be possible with a cylindrical cutter head or a conical head with its base arranged away from the work, and thereby permits the turning of lasts having more sharply projecting upper instep portions.

The improvements in which the present invention consists may be applied to and used in connection with any lathe adapted to turn irregular work, and in the following specification and the drawings forming a part of the same are described and shown as applied to a last lathe of standard pattern, without however implying an intention to restrict the scope of the present invention to that or any other particular turning lathe. In the drawings,

Figure 1 represents in front elevation a

standard last lathe to which my present invention is applied;

Fig. 2 is an elevation as seen from the right of Fig. 1;

Fig. 3 is a plan view of the bed of the lathe showing the cutter and its drive, the model guide, and indicating the relation which the cutter and guide occupy to the work and the model, respectively.

Fig. 4 is a plan view of the adjustable guide pulley which forms a part of the drive for the cutter.

Fig. 5 is a projection of Fig. 4, in the direction of the arrow.

Fig. 6 is a side elevation of my improved cutter head.

Fig. 7 is an end elevation of the cutter head with the finishing cutter removed.

Fig. 8 is an end elevation partly in section of the finishing cutter shown in Fig. 6.

Fig. 9 is a side elevation and

Fig. 10 an end view of another form of cutter head and cutters embodying the general principles but in different form of the cutter head and cutters shown in Figs. 6, 90, 7, and 8.

The same reference characters indicate the same parts in all the figures.

Referring to Figs. 1, 2, and 3, 11 represents the bed of a last lathe of standard form which is supported upon legs 12 and has an overhanging frame 13-13 on which a swing 14-14 is hung by means of the pivot rod 15. The swing is provided with the usual centers 16 and 17 for the model 18, the centers 19 and 20 for the work or block 21 and the supporting driving and adjusting means for such centers, which, forming no part of the present invention require no description.

The bed has guideways 22, 23, and 24 on which rest the carriage 25 for the model guide and the carriage 26 for the cutter spindle, such carriages being movable in unison along the guideways in directions generally parallel to the axes of rotation of the model and of the work piece, and being so moved at the same speed or at different speeds by any usual or other mechanisms suitable for the purpose.

Standards 27 and 28 on the cutter spindle carriage have bearings in which the cutter spindle 29 is rotatably mounted, said bearings being arranged to hold the spindle at an acute angle to the axis of rotation of the work and preferably, though not necessarily, in the same horizontal plane with the axis of rotation of the work. 30 represents the cutter head on the end of the spindle nearest the work.

In the apparatus shown, the cutter spindle is rotated at a high rate of speed from a drum 31 on the main shaft 32 by a belt which passes under the drum and over a pulley 33 on the spindle and between guide pulleys 34

and 35. The drum is arranged as usual with its axis parallel to the line of travel of the cutter carriage and is long enough to permit the necessary travel of such carriage without causing the belt to pass over either end. A feature of the machine consists in the arrangement of the guide pulleys 34 and 35 and the provision for adjustment of the pulley 35 to cause the belt to run true over the spindle pulley 33 without working over either end thereof. Pulley 34 is mounted on a fixed stud 36 secured to the under side of the cutter carriage on an axis parallel, or approximately so, to the axis of the drum. Pulley 35 is mounted on a pivot stud 37 secured in a head 38 which is adjustably connected to a bracket 39 by means of a bolt 40 passing through a flange 41 on the bracket, and the bracket is adjustably angularly connected to the under side of the carriage by a bolt 42. Bolt 42 is vertical, and bolt 40 is horizontal, and is also perpendicular to the bolt 42. The bracket and the pulley can be adjusted angularly about the bolt 41 and the pulley can be further adjusted angularly with respect to the bracket about bolt 40. This gives capacity for adjustment of the pulley in two directions and enables it to be so placed that the belt will run properly between the drum and the cutter spindle pulley.

The model guide 43 is a disk substantially equivalent in size to the surface of revolution generated by the finishing cutter of the cutter head and is rotatably mounted on an axis parallel to that of the cutter spindle and mounted on a bar 45. The bar 45 is horizontally adjustable, forward or back, on the width grading slide 44', which is mounted slidably on the standard 44 of the model wheel carriage, as is well understood by workers in this art.

The preferred form of my novel cutter head is shown in detail in Figs. 6, 7, and 8. It comprises three roughing cutters 46, 47, and 48 and a finishing cutter 49, all mounted on the spindle 29. The roughing cutters are substantially alike except for differences of diameter and a variation in external form of the cutter 48. Each consists of a collar or hub 50 which fits the spindle and is in close abutting terminal contact with the adjacent hubs and is provided with a keyway to receive a spline or key 51 on the spindle, and has a number of arms 52, each provided with a lip 53 sharpened at one edge 54 to act as a knife. The arms are at one end of the hub and the sharpened lips extend toward the other end of the hub, whereby the cutting edge or knife portion of the lip extends the entire length of the cutter. It should be noted from Fig. 7 that each of the arms is recessed at the side toward the cutting edge of the lip so that such cutting edge crosses the arm as well as extends beside the same.

Preferably the outer surfaces of the knife lips and the knife edges are elements of a conical surface of which the larger diameter is toward the end of the spindle. The three cutters 46, 47, and 48 have generally similar surfaces of gradually increasing diameter so that collectively the surface of revolution described by their cutting edges is approximately a continuous cone. While I have shown three roughing cutters I have not intended thereby to limit the invention to a cutter head having neither more nor less than three cutters. The finishing cutter is on the extreme end of the spindle, that is at the base of the cutter head, and is the nearest of all the cutters to the axis of the work, as well as being the most remote of the cutters from the axis of the spindle. It is formed with arms each of which is provided with a transverse aperture 55 which is enlarged at one side of the arm to form a cutting edge 56. Such cutting edge is reinforced and supported by the material at each end of the cutter, instead of being supported only at one end, as is the case with the other cutters.

In the cutter head shown in Figs. 9 and 10 there are three cutters 57, 58, and 59 which are preferably employed as roughing cutters in connection with a finishing cutter 95 such as the cutter 49; although if desired the cutters 57 and 58 may be employed for roughing and the cutter 59 for finishing. In the construction shown these cutters are substantially like the cutters 46, 47 and 48 with this exception that the cutting edges and the lips or webs on which said cutting edges are formed are curved longitudinally instead of being substantially straight. If desired the three cutters shown in Fig. 9 may be employed as roughing cutters in connection with a finishing cutter which may be the same as the finishing cutter 49. The pear or bell-shaped form of the cutter shown in Fig. 9 is somewhat more accentuated than is that shown in Fig. 6, the cutter 59 projecting relatively farther beyond the surface generated by the other cutters than the cutter 56. This form permits the finishing cutter to drop to the ball while the roughing cutter is working on the upper part of the instep, with a greater inclination of the axis than would be possible if the generating line of the lateral conical surface of the cutter were exactly straight. The advantage of such structure in the cutting of high coned lasts has already been suggested.

The finishing cutter has the same outer diameter as the guide wheel 43 and its edge is curved on the same radius as the transverse curvature of the rim of such wheel, whereby the surfaces formed by the finishing cutter may conform exactly to the surfaces on the model on which the guide acts, except for such differences as are caused by 130

rotating the work in reverse direction to the model, and by length and width grading. The angle between the cutter axis and the axis of the work is considerably less than 5 45°. In the machine shown it is about 30°. I have found after a great deal of experimentation that this angle greatly increases the advantages of my prior invention above discussed as compared with the machine 10 closed in said earlier patent in which the angle was about 80°. The advantage of the "draw cut" is very much accentuated. It is necessary to incline the cutter axis of a "small" cutter head in order to carry out of 15 the way of the work the bearings and the arbor which have to be rather rugged to perform properly the heavy work they have to do. The difficulties inherent in machines previously suggested, in which the cutter 20 axis was inclined in the wrong direction (among others, excessive vibration of the cutter arbor due to compressive stresses, and a tendency to catch and dig into the work) have been avoided by inclining the cutter 25 axis forward instead of backward, as in the machine of the prior patent, and the axis is brought much more nearly parallel to that of the work than in my prior machine so that there is far less bending moment on the 30 arbor with correspondingly less vibration and chatter. At the same time, the angle is ample to secure clearance between the work and the cutter head supporting mechanism.

Further, the new angle results in the production of smoother work than was possible 35 at the 80 degree angle. There are many places on a last where the wood fibers run out into the surface. A blade on an axis too far from parallelism with the fibers will cut 40 directly against the grain on some of these parts and cause roughness in the surface cut. Also, the tip of the cutter has small peripheral velocity and consequently cuts less freely than other parts of the cutter. 45 These difficulties are avoided by the new angle between the cutter and work axes. The two axes are near enough to parallelism to avoid any appreciable effects of cutting against the grain, and the blades of the cutter head 50 are all placeable far from the dead point.

The change in the angle which characterizes the present invention also secured, among others, several further very important advantages not obtainable with the machine of the patent. A model wheel the axis 55 of which is near the perpendicular to that of the work must be nearly or quite spherical in order to enter the concavities of the model. This is because the effective curvature of a disk-shaped model wheel is the curvature of its projection on a plane perpendicular to the axis of the work. This 60 will be much flatter than the curvature of a principal section of the wheel perpendicular 65 to its axis of rotation if such axis makes a

large angle with that of the work. A cutter head of the spheroidal form is expensive to construct and to keep in order. The blades of a last lathe cutter head should be easily removable for grinding, and easily adjustable and interchangeable, and these objects are very difficult of attainment with a spheroidal cutter head. The inclining of the axis below 45° enables me to use a disk-shaped model wheel with a finishing cutter 70 of corresponding shape. Such an instrumentality is of a radically different type and is much easier to construct in a practical manner and to keep in order.

A further advantage was found in the 80 superior capabilities of the new machine in cutting so-called "high coned" lasts. In lasts of this type the instep ridge runs up to a point considerably higher than its usual point of termination and then descends 85 sharply to the flat top of the cone. A cutter head which is inclined far from the work axis cannot cut such a last because after the front of the projection has been cut the model wheel will hang up on it and prevent 90 the cutter from working down the rear side of the projection. The new angle enables the machine to cut lasts with much higher, sharper cones than the old.

The cutter head itself, by virtue of its 95 shape, possesses several advantages over the substantially cylindrical form shown in said previous patent. It is conical or pear shaped, with the large end toward the work. The general line of the cutting edges is thus 100 arranged roughly parallel with the ridge of the instep. This structure has, among others, the following advantages. The finishing blades are at the large end and are consequently given a greater linear velocity 105 than the roughing blades which, in their turn, are closer to the axis and can be fastened securely and rigidly. It is not necessary that the roughing blades move so rapidly as the front blades since they are not 110 obliged to do smooth work while it is necessary that they be strong and durable.

Secondly, it is necessary that the cutter axis project several inches toward the work, beyond its bearing, in order to insure that 115 the block will not strike the necessarily large and substantial bearing as it rotates. The roughing and finishing cutters are arranged side by side in order with their hubs in abutting terminal contact along this part 120 of the shaft, and thereby stiffen it, distribute the cutting duty along it, thus diminishing the bending moment upon it. This advantage was present to a certain extent in my prior machine. This construction of the 125 cutter head, however, in connection with the new angle, distributes the cutting action over a considerable part of the length of the block, thereby permitting the removal of the same amount of material per second 130

in thinner chips than would otherwise be the case, and with a consequently smaller expenditure of power and less vibration. At the same time the conical shape of the 5 cutter head, when the cutters are arranged as above explained, tips the axis to a more acute angle with the axis of the work than would be possible if the cutter head were cylindrical or conical with its small end toward the work, and this facilitates the cutting 10 of high coned lasts.

This additional acuteness of the angle of the shaft also enhances the advantage already discussed relative to the drawing of 15 the cutter over the work by tensile rather than compressive action of the cutter shaft with the consequent creation of minimum bending stresses in it, and diminution of the liability to dig into the work. There is of 20 course a limit to the extent to which the line of cutting edges can be inclined—determined by the condition of things at the time the roughing cutter is working on the upper part of the instep and the finisher is 25 treating the top of the ball. It is advantageous to run the cutter shaft at a more acute angle than that made by the instep ridge with the work axis, and the conical cutter head permits this. Angling the shaft 30 too much toward the axis would bring it too near parallelism so that the small cutter head could not be used. I have found that an angle of about 30° is close enough to parallelism to secure advantageous action of the 35 shaft and at the same time is far enough from parallelism to secure the advantages of the small model wheel and cutter and of the compact high speed cutter head.

The formation and arrangement of the 40 cutters not only provides a combined great length of cutting edge, but also provides what is in effect a plurality of such cutting edges and divides each edge into a number of segments which are disposed out of alignment 45 so as to bring them into action successively and distribute the cutting effort; while at the same time providing ample spaces between the adjacent blades, and between the blades and hubs of the roughing 50 cutters, and through the arms of the finishing cutter, for escape of chips. If a greater or less effective length of cutting edge is required, additional cutters may readily be placed on the spindle, or one or more of the 55 cutters shown may be as easily removed. The cutter instrument thus has great flexibility for expansion and contraction without modifying its other characteristics.

In explanation of the terms employed in 60 this description and in the following claims, I would say that each of the cutters may be called a cutting unit, having any desired number of blades, the cutting edge of each blade constitutes a segment or zone of the 65 collective cutting edge which is provided by

the contiguous blades of respectively adjacent cutters. The entire collection of cutting units constitutes the complete cutter instrument.

What I claim and desire to secure by Letters Patent is:—

1. A machine for turning irregular forms comprising a rotatable work holder, a cutter holder, one of said holders being movable relatively to the other in a line parallel to the axis of rotation of said work holder, and a cutter of generally conical formation mounted on said cutter holder to turn about an axis extending at an acute angle to the axis of rotation of the work holder in the direction of progressive cutting action, and being further arranged with its base nearest to the axis of the work. 70

2. A machine for turning irregular forms comprising a work holder adapted to support and rotate a work piece, a cutter holder, one of said holders being movable relatively to the other so as to cause a progressive cutting action in a direction approximately parallel to the axis of rotation of the work, and a cutter spindle mounted in said cutter holder making an acute angle with the axis of the work in the direction of progressive cutting action and having an end projecting in proximity to the work, and a cutter instrument mounted on said projecting end having an advance rough cutting portion and a following finishing portion, said portions arranged to travel in a surface of revolution which is approximately conical and arranged with that part which forms the base of the cone nearest to the axis of the work. 85

3. A machine for turning irregular forms comprising the combination of work holding means adapted to support and rotate a work piece, a cutter holder mounted to travel in a direction approximately parallel to the axis of rotation of the work, a cutter spindle carried by said cutter holder projecting therefrom toward the axis of the work, the angle between said spindle and axis in the direction of cutting feed being acute, and a cutter instrument mounted on said cutter spindle adjacent to the projecting end thereof, and comprising rough cutting and finishing portions; the rough cutting portion being in advance of the finishing portion and being also nearer to the spindle than the latter, whereby the line between the surfaces of revolution of said portions at the side thereof next to the work makes an angle with the axis of the work which is greater than the aforesaid angle between said axis and the spindle. 105

4. A machine for turning irregular forms comprising a work holder adapted to support and rotate a work piece, a cutter holder, one of said holders being movable relatively to the other so as to cause a progressive cut- 110 115 120 125 130

ting action in a direction approximately parallel to the axis of rotation of the work, a cutter spindle mounted in said cutter holder making an acute angle with the axis 5 of the work in the direction of progressive cutting action and having an end projecting in proximity to the work, and a cutter instrument mounted on said projecting end having an advance rough cutting portion 10 and a following finishing portion, said portions arranged to travel in a surface of revolution which is approximately pear-shaped and arranged with that part which forms the thick part of the pear nearest to the axis 15 of the work.

5. A machine of the class described comprising a work holder adapted to support and rotate a work piece, a cutter holder, one of said holders being movable relatively to 20 the other to cause a progressive cutting action in a direction approximately parallel to the axis of rotation of the work, and a cutter spindle mounted in said cutter holder making an angle of substantially less than 25 45° with the axis of the work in the direction of progressive cutting action.

6. A machine of the class described comprising a work holder adapted to support and rotate a work piece, a cutter holder, one 30 of said holders being movable relatively to the other to cause a progressive cutting action in a direction approximately parallel to the axis of rotation of the work and a cutter spindle mounted in said cutter holder in a 35 position of approximate parallelism with an adjacent instep ridge of a last being cut from the work piece.

7. A machine of the class described comprising a work holder adapted to support 40 and rotate a work piece, a cutter holder, one of said holders being movable relatively to the other to cause a progressive cutting action in a direction approximately parallel to the axis of rotation of the work, a cutter 45 spindle mounted in said cutter holder making an angle of substantially less than 45° with the axis of the work in the direction of progressive cutting action and having an end projecting in proximity to the work, and 50 a cutter instrument mounted on said projecting end having an advance rough cutting portion and a following finishing portion, said portions arranged to travel in a surface of revolution which is approximately 55 pear-shaped and arranged with that part

which forms the thick part of the pear nearest to the axis of the work.

8. A machine of the class described comprising a work holder adapted to support and rotate a work piece, a cutter holder, one 60 of said holders being movable relatively to the other to cause a progressive cutting action in a direction approximately parallel to the axis of rotation of the work, a cutter spindle mounted in said cutter holder in a 65 position of approximate parallelism with an adjacent instep ridge of a last being cut from the work piece and having an end projecting in proximity to the work, and a cutter instrument mounted on said projecting 70 end having an advance rough cutting portion and a following finishing portion, said portions arranged to travel in a surface of revolution which is approximately pear-shaped and arranged with that part which 75 forms the thick part of the pear nearest to the axis of the work.

9. In a machine of the class described, a work holder and a cutter holder arranged for relative traverse to effect progressive cutting action on the work, a cutter instrumentality mounted on the cutter holder with its axis inclined acutely toward the direction of relative cutting feed at an angle substantially less than 45°, and a disk-shaped model 80 wheel arranged on a similarly arranged axis, having a diameter not substantially greater than the thickness of the largest model used in practice, the cutter instrumentality having 85 a finishing portion of corresponding 90 shape.

10. A machine of the class described comprising a work holder adapted to support and rotate a work piece, a cutter holder, one of said holders being movable relatively to 95 the other to cause a progressive cutting action in a direction approximately parallel to the axis of rotation of the work, a cutter spindle mounted in said cutter holder and making an angle of substantially less than 100 45° with the axis of the work in the direction of progressive cutting action, and a cutter mounted on the spindle having a finishing portion of disk shape, with the finishing cutting edges on its periphery, the effective diameter of the finishing portion being substantially greater than its thickness.

In testimony whereof I have affixed my signature.

FRANK S. BUCK.

It is hereby certified that in Letters Patent No. 1,330,841, granted February 17, 1920, upon the application of Frank S. Buck, of Springfield, Vermont, for an improvement in "Machines for Turning Irregular Forms," an error appears in the printed specification requiring correction as follows: Page 5, line 120, claim 3, for the words "line between" read *general direction of the line joining*; and that the said Letters Patent should be read with this correction therein that the same may conform to the record of the case in the Patent Office.

Signed and sealed this 6th day of July, A. D., 1920.

[SEAL.]

M. H. COULSTON,

Acting Commissioner of Patents.

Cl. 142—15.
